(57) **CLAIM**

The ornamental design for a fire pit cover as shown and described.

DESCRIPTION

FIG. 1 is a front, left and top perspective view of a fire pit cover, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 depicts an enlarged detail view of portion 9 shown in FIG. 2.

The broken lines in the drawings depict portions of the fire pit cover that form no part of the claimed design. The dot-dash broken lines in the drawings designating the boundary of the enlarged detail view, form no part of the claimed design.

1 Claim, 9 Drawing Sheets
